BINDER FOR TEXTILE MACHINERY

Filed Feb. 28, 1928

Inventor
Henry Pulster,
By
J. Stuart Freeman
Attorney.

UNITED STATES PATENT OFFICE.

HENRY PULSTER, OF PHILADELPHIA, PENNSYLVANIA.

BINDER FOR TEXTILE MACHINERY.

Application filed February 28, 1928. Serial No. 257,628.

The object of the invention is to provide improvements in certain details of the construction and operation of textile machinery, and more particularly in a type of machine used to knit tubular articles of various types.

In circular knitting machines, especially when several yarns of different size, color, or material, are being used, the threads which are severed and not actually being worked at a given moment are constantly in danger of slipping, and in fact often do slip, free from the single binder heretofore employed and comprising metal against metal, with the result that each machine requires constant tending, so-called press-offs and drop stitches frequently occurring, with the result that the tubular product when completed can only be used in a finished article of "second" quality, or must be rejected altogether.

20 The object of the invention therefore is to provide an improvement in the mechanism that holds the ends of the severed threads, and through which the threads of various sizes, colors, or materials, are supplied to the needles. Also, instead of merely the single spring-pressed liftable binder heretofore employed in direct contact with a metal surface or platen (except as shown in copending application Ser. No. 249,224), a plurality of 25 resilient auxiliary fingers are used, these latter being in constant engagement with the surface over which the threads pass, and at all times cooperating with each other and the liftable binder, to positively prevent the escape of a single thread at any time from a position accessible to the needles.

A further object is to provide means for retaining the cushion or platen and protecting the edges of same in such manner that threads cannot enter beneath and loosen a corner or edge portion and start the eventual separation of the platen from its support. In addition to supporting the platen upon the platform and surrounded by a beading or the like to protect its edges, the same or an additional platen may be operatively supported and gripped in such manner by the liftable binder as to produce substantially the same desirable result, in which latter case the 30 platform is preferably provided with one or

more ridges or corrugations which impinge against and create corresponding recesses in the surface of the platen, and thus increase the frictional contact of the binder with the platform and decrease the possibility of 35 threads of yarn slipping therethrough or laterally therefrom.

In this present invention there is also provided a more positive connection than heretofore between the actuating lever and the liftable binder, eliminating springs and such less positive elements, and substituting therefor a series of link motions, one of which positively actuates the liftable binder and secures it in operative position, until such time as 65 another link motion releases and lifts said binder to permit the free passage of threads therebeneath.

With these and other objects in mind, the present invention comprises further details 70 of construction and operation which are fully brought out in the following description when read in conjunction with the accompanying drawings in which Fig. 1 is a front elevation of one embodiment of the invention; Fig. 2 75 is a top plan view of the same; Fig. 3 is a rear elevation of the same; Fig. 4 is a vertical section on the line 4-4 of Fig. 3; and Fig. 5 is a fragmentary section showing a modified method of supporting the binder platen. 80

Referring to the drawings, the improved attachment comprises primarily a platform 1 from which rises upon one side a flange 2, having a restricted upwardly extending portion 3, which in turn comprises a bracket extension 4, provided with elongated apertures 5 for adjustably securing the device to a textile machine. To an upwardly extending lug 5' carried by the bracket 4 there is pivotally secured a lever comprising an elongated 90 arm 6 extending in one direction and a preferably curved arm 7 extending generally in the opposite direction and having a hooked terminal portion 8 adapted to be engaged by a connecting rod (not shown) which extends 95 downwardly and effects an operative connection with suitable portions of the textile machine upon which the attachment is mounted.

The flange 2 terminates forwardly in spaced relation with the adjacent edge por- 100

tion 1' of the platform, a rectilinear edge 9 of said platform comprising a cutting edge against which is adapted to oscillate a shearing knife 10, pivotally mounted at 11 upon the flange 2, and having an oppositely extending lever projection 12 which is connected through a link 13 with the elongated end portion 6 of the operating lever 6-7. Said link is in turn provided with a laterally extending off-set or arm 14 which may be integral therewith or may be removably and adjustably secured thereto by means of a bolt or other suitable means 15.

To the radially inner surface of the upwardly extending portion 3 there is pivotally secured a liftable binder having a head 16, extending in one direction and in the other direction comprising an extension 17 which is adapted to be directly engaged by the link 14 arm or off-set 14 when the operating lever 6-7 moves in one direction to raise the binder 16 from cooperation with the upper surface of the platform 1.

Also mounted pivotally upon the projection 3 is a lever comprising an arm 18 normally in the path of and adapted to be encountered and moved by the arm or off-set 14, and a second arm 19 which extends angularly into proximity and is adapted to cooperate with the upper surface of the binder 16.

From the platform 1 there also extends upwardly a lug 20 which adjustably supports a freely extending guide 21, adapted to operate to guide threads beneath a pair of resilient binders 22 which are at all times in yielding cooperation with the surface of the platform 1 and are adjustably and removably secured thereto by means of a set screw or the like 23.

40 The under surface of the binder 16 is preferably bifurcated longitudinally so as to provide a plurality of substantially parallel depending ridges 24 which cooperate with and form depressions or corrugations in the upper surface of a platen 25, of yielding material such as leather or the like, closely adjacent to the cutting or shearing edge 9 of said platform and between said cutting edge and the position of the resilient binders 22.

50 On the other hand, referring to Fig. 5, a binder 16' may be provided with more widely spaced flanges 24', between which is secured a platen 26 of leather or the like, into the under surface of which grooves or corrugations 55 27 are formed by cooperation with upwardly extending corrugations or ridges 28 upon the upper surface of the platform 1, whether said last-named corrugations form integral extensions of said platform or are parts of a separate plate 29 which may be secured to said platform in any desired manner.

In the operation of this device, the parts thereof shown in Fig. 1 are in, what will be referred to as, a raised position, the binder 60 16 being raised freely from the platform 1

and the shearing knife 10 raised above the cutting or shearing surface 9 of the platform. As an operating rod connected with the hooked end 8 of the actuating lever 6-7 moves downwardly, said lever is moved about its pivotal support in such manner as to raise the link 13 and arm or offset 14 until it encounters the lever arm 18, causing the oppositely and downwardly extending lever arm 19 to press the binder 16 into binding co-operation with said platform, the shearing knife 10 simultaneously moving downwardly through connection with the link 13 and cutting or shearing the yarn in a well-known manner.

When the actuating lever 6-7 is moved again into the position shown in Fig. 1, the link 13 causes its arm or off-set 14 to move downwardly and to press against the binder extension 17, raising the binder 16 free from engagement with the platform and separating the shearing knife 10 from the cutting edge 9, thus raising the lever arm 19 so as to reset it and the lever arm connected thereto, for repeating the opposite movement of the device as before described. Although the yarn 30 is for a time not held by the liftable binder 16, it continues to be held yieldingly by the resilient binders 22 in such manner that it can be picked up when needed by the adjacent operating parts of the textile machine to which the attachment is applied.

Having thus described my invention what I claim and desire to protect by Letters Patent of the United States is:

1. An attachment for textile machines, comprising a platform, a binder pivotally carried thereby and extending upon opposite sides from its pivotal support, an actuating lever upon being moved in one direction cooperating with one end portion of said binder to release the same, and when moved in the opposite direction cooperating with the opposite end portion of said binder to close the same.

2. An attachment for textile machines, comprising a platform, a binder pivotally carried thereby and extending in opposite directions from its pivotal support, an actuating lever, a link connected to said lever and having an offset adapted to engage and shift one end of said binder when moving in one direction, and a second lever pivotally mounted and extending between said offset and the opposite end portion of said binder, whereby movement of said actuating lever in the operation causes said offset to engage said last-mentioned lever and thereby cause said binder to move in the opposite direction.

3. An attachment for textile machines, comprising a platform, a shearing knife movably carried by said platform, an actuating lever, a link connecting said lever to said knife and having an offset, a binder pivotally supported by said platform and extending in

opposite directions from its pivotal support,
said offset cooperating with one end portion
of said binder to move it in one direction
simultaneously with the movement of said
5 knife, and a second lever also pivotally sup-
ported by said platform and operative to con-
nect said offset with the opposite end por-
tion of said binder to move the latter in the
opposite direction with a corresponding
10 movement of said first lever and said knife.

In testimony whereof I have affixed my
signature.

HENRY PULSTER.
